UNITED STATES PATENT OFFICE.

EDMUND OCUMPAUGH, 2d, OF ROCHESTER, NEW YORK.

PRINTING-MACHINE.

1,138,778.

Specification of Letters Patent.

Patented May 11, 1915.

Application filed January 23, 1914. Serial No. 813,875.

To all whom it may concern:

Be it known that I, EDMUND OCUMPAUGH, 2d, a citizen of the United States, and resident of Rochester, in the county of Monroe and State of New York, have invented certain new and useful Improvements in Printing-Machines, of which the following is a specification.

This invention relates to machines of the type in which any of a series of characters or words may be impressed selectively upon a check-blank, or other article, through the operation of manually-operable means.

The invention is particularly applicable to machines of the type commonly designated as "check-writing machines", wherein the printing characters are arranged, upon a type carrying member, in the form of a series of words expressive of different numerical amounts, this member being so mounted as to be movable for the two purposes of bringing the characters thereon selectively into operative position, and of advancing or feeding the work through the engagement of the type therewith.

One object of the invention is to provide a machine of the type in question with manually-operable means, of simple construction, whereby movements of two different characters may be imparted to the type-carrying member through the agency of a single manually-operable member movable in two modes or directions. To this end I employ a type-carrying member which is so mounted as to be movable in two directions, preferably rotatively and axially, and I connect this type-member with a manually-operable member which has a movement of translation, by which one movement of the type-carrying member is produced, and a rocking or angular movement by which the other movement of the type-carrying member is produced.

Another object of the invention is to so correlate the movements of the platen, which co-operates with the type-carrying member, with the movements of the latter, that this platen shall be automatically thrown into operative position during that one of the movements of the type-carrying member which is utilized as the combined impressing and work-feeding movement, and to this end I employ cam-mechanism actuated by the manually-operable member and adapted to throw the platen into and out of operative position immediately after

the commencement of the operative and return movements, respectively, of the type-carrying member.

Another object of the invention is to provide a machine of the type in question with simple and convenient means whereby the ink-rollers are caused to follow the movements of a wheel, and are also mounted removably in their operative positions, and to this end I employ ink-rollers which are movable axially in conjunction with the axial movements of the type-wheel, being constrained to such movement by interengaging flanges and slotted members connected with the ink-rollers and the type-wheel, respectively, and I further mount these ink-rollers on base-members which are slidable, longitudinally, out of operative position, provision being made for the disengagement of the connections between the ink-rollers and the type-wheel, to permit such longitudinal removal of the rollers.

Another object of the invention is to provide a machine of the type in question with simple automatic means for retaining the work against accidental movement between successive feeding movements, and to this end I employ a retaining device or work-presser which is connected with, and actuated by, the mechanism by which the platen is controlled, so as to be thrown into operation alternately with the platen.

Other objects of the invention, and the features of construction by which they are carried out, will be set forth in connection with the following description of the preferred embodiment of the invention.

In the accompanying drawings—Figure 1 is a plan-view of a check-writing machine embodying the present invention; Fig. 2 is a right-hand side-elevation, partly in vertical section; Fig. 3 is a plan-view showing, in detail, the type-wheel; Fig. 4 is a vertical section on the line 4—4 in Fig. 2; Fig. 5 is a section on the line 5—5 in Fig. 2; and Fig. 6 is a partial horizontal section showing, in plan-view, the arrangement of the ink-rollers.

In the illustrated embodiment of the invention, which is a machine adapted for filling in the amounts of the bank checks, the printing instrumentalities comprise a type-wheel 10 and a co-operating platen-roller 11. As shown in Fig. 3, the types are arranged upon the type-wheel so as to produce a series of words reading parallel with the

axis of the wheel and expressive of numerical amounts, dollars, cents, etc., this series extending peripherally around the cylindrical surface of the wheel. The type-wheel 5 is mounted upon a fixed horizontal shaft 12, so that it may have both rotative and axial movements therein. The rotative movements are utilized, in the present case, as the selective movements by which the required 10 characters are brought into operative position above the platen-roller 11, while the axial movements are utilized as impressing and feeding movements, the platen, during the axial movement of the type-wheel toward the left from the position shown in 15 Fig. 4, being raised to force the work into engagement with the type-wheel. The platen is preferably provided with ridges or serrations, as shown, so as to partially cut the 20 paper of the check in addition to printing the characters with ink.

The manually-operable member by which the selective and impressing operations of the printing-means are produced is in the 25 form of a handle 13, projecting at the right-hand side of the machine. This handle is fixed to a plate 14 which moves both laterally and angularly upon a rock-shaft 15, journaled in horizontal position in the casing of 30 the machine. At its lower edge the plate 14 is provided with teeth forming a rack 16, and this rack engages gear-teeth 17 formed at the bottom of an annular slot in the type-wheel 10. Accordingly, a sliding movement 35 of the plate along the shaft 15, such as is produced by moving the handle 13 toward or from the user, causes rotation of the type-wheel, this rotation being the selective movement above referred to. In order that the 40 handle 13 and the plate 14 may also produce the axial movement of the type-wheel constituting the impressing and feeding movement thereof, the rack 16 is formed with a 45 partially cylindrical cross-section, as shown in Fig. 4, so that it may coöperate pivotally with the slot in the type-wheel. Accordingly, if the handle 13 be depressed, by an 50 angular movement about the axis of rotation of the shaft 15, the rack is swung rearwardly and carries the type-wheel with it, along the shaft 12, while the return movement of the type-wheel is coincident with the rise of the handle 13 to its normal upper 55 position.

To indicate to the user the position to which the type-wheel is moved by the selective operation, a pointer 19 is mounted loosely upon the shaft 15, in a slot in the plate 14, so that the pointer moves along 60 the shaft with the plate but does not participate in the rocking movements of the plate or the shaft. This pointer projects upwardly through a slot in the casing of the machine, and coöperates with a graduated 65 scale 20.

In order that the platen-roller 11 may be thrown into and out of operative position at suitable times, it is journaled on an arm 21 fixed to a rock-shaft 22, the rock-shaft being journaled in fixed bearings on the frame of 70 the machine. A second arm 24 on the rock-shaft is connected with a spring 23, which tends constantly to rock the platen-roller upwardly into operative position. The movements of the platen-roller and its supporting-mechanism are controlled, however, by means connected with the manually-operable mechanism. These means comprise a link 25, which is pivoted to the arm 24, and guided near its upper end so as to move vertically, this link having a pin 26 which co-operates with cam-mechanism mounted on an arm 27 depending from the rock-shaft 15. This shaft is provided with a longitudinal groove 28 engaged by a sliding key 29 in the plate 14, so that the shaft 15 participates in the rocking movements of the handle and the plate 14 which produce the axial movements of the type-wheel. The arm 27 is also fixed to rock with the shaft 15. 80

A projection 30 from the arm 27 normally overhangs the pin 26 on the link 25, and retains the link in depressed position, thus holding the platen-roller out of operative position, against the tendency of the spring 95 23. When the handle 13 is depressed, however, to produce an impressing and feeding operation of the type-wheel, the first part of this movement removes the cam-projection 30 from engagement with the pin 26, and the spring 23 then at once operates the mechanism to raise the platen-roller into coöperative relation with the type-wheel. During the continued movement of the parts a pawl 31, which is pivoted, between its ends, upon the arm 27, passes beneath the pin 26. This pawl has a straight upper surface, while its lower surface comprises two portions 32 and 33. The portion 32, at the left-hand side of the pivot upon which the pawl is mounted, is circular in form, while the portion 33 constitutes, in effect, a cam-surface at an acute angle to the part 32. During the left-hand movement of the arm 27, as shown in Fig. 5, the pin 26, at the last part of this 100 movement, engages the right-hand end of the pawl, and rocks this end momentarily downwardly, so that the right-hand end of the pawl may pass clear beyond the pin. The pawl then returns automatically to the 105 position illustrated in Fig. 5, so that at the commencement of the return movement of the arm 27 the cam-surface 33 is in position to engage the pin 26. Upon the subsequent return movement of the arm 27, coinciding with the return movement of the type-wheel, the first portion of this movement causes the cam-surface 33 to depress the pin 26 quickly, and with it the link, whereby the 110 platen is moved quickly downward out of 115 120 125 130

operative position, thus releasing the work and preventing it from being drawn back by the type-wheel. The parts are retained in this position, during the remainder of the 5 return movement, by engagement of the pin 26 with the part 32 of the pawl 31, this part being at this time raised to a position in which it is in alinement with the lower surface of the cam-projection 30. A stop-lug 10 34 on the arm 27 determines this position of the pawl. The parts are thus returned to the position of Fig. 5 with the platen-roller in its normal depressed position.

In order that the check-blank may be held 15 securely against accidental movement during the return movement of the type-wheel which intervenes between successive printing and feeding movements, I employ a work-presser in the form of a pin 35, which 20 is threaded in a left-hand extension on the arm 21 and adjustably fixed by a lock-nut 36. The check-blank is introduced between the work-table 37 and a stripper-plate 38 located a short distance above it, and the 25 presser 35 is adapted to force the blank upwardly and clamp it against the stripper-plate, thus retaining it against movement after each printing operation. It will be apparent that at each downward movement of 30 the platen-roller the work-presser 35 is moved upwardly into operative position, so that its operation alternates with that of the platen-roller, and with the successive printing and feeding movements of the type- 35 wheel.

To assist in inserting the check-blank in the proper position in the machine, an adjustable gage 39 is mounted between the work-table 37 and the stripper-plate 38, this 40 gage being fixed in adjusted position by thumb-nuts 40.

The inking-mechanism by which ink is supplied to the type-wheel is shown particularly in Figs. 2 and 6. Two ink-rollers 41 are employed, which are constantly in engagement with the type-wheel, and are mounted loosely upon parallel shafts 42 so that they can slide axially during axial movement of the type-wheel. To correlate 45 the axial movements of the ink-rollers and the type-wheel each ink-roller is provided with an annular flange 49, which engages the annular slot in the type-wheel, as shown in Fig. 2. In order that the type-rollers may 50 be pressed constantly against the type on the type-wheel, the shafts 42 are carried by upwardly-projecting arms 43 fixed to rock-shafts 44, these rock-shafts being pivotally mounted upon base-plates 45. Springs 46 55 tend to rock the shafts 44 and the arms 43 in a direction to force the ink-rollers against the type-wheel.

In order that the ink-rollers may be conveniently removed, when it is necessary to 60 supply them with ink, the base-plates 45

are mounted slidably between guide-flanges 47 on the stripper-plate 38, and openings are provided in the front of the casing, normally covered by a removable plate 48. Upon the removal of this plate the ink-rollers may be swung away from the type-wheel, so as to disengage their flanges 49 therefrom, and the base-plates 45 may then be slid forwardly out of the guide-flanges 47, thus removing the ink-rollers and their supporting-means at the front of the machine. It is not necessary to remove them entirely from the casing, however, since the ink-rollers are considerably shorter than the base- 75 plates, so that they may project free of the casing while the base-plates still engage the forward ends of the guide-flanges.

It is essential that the type-wheel, after each selective movement, be brought to and held in a position in which one of its rows 80 of characters is in exact registration with the platen-roller 11. To insure such correct registration I provide the type-wheel with a plate 50, preferably of hardened steel, which has serrations upon its edge, as shown 85 in Fig. 3, coinciding with the spaces between adjacent rows of type. This plate co-operates with a detent-plate 51 depending from the top of the casing of the machine. The detent-plate is so adjusted that it shall exactly register with one of the spaces in the plate 50 when the type-wheel is in proper position with respect to the platen-roller, and until the wheel has been brought to such a position it is impossible for the user to 90 move the type-wheel longitudinally to produce an impressing and feeding operation.

It will be apparent that the two movements of the handle 13, by which the selective and impressing operations of the printing-means are produced, may be performed 95 very readily in succession, using one hand for this purpose, while the check-blanks are introduced lengthwise at the right-hand side of the machine and discharged lengthwise at 100 the other side of the machine.

My invention is not limited to the embodiment thereof hereinbefore described and illustrated in the accompanying drawings, but it may be embodied in various other 110 forms within the nature of the invention as it is defined in the following claims.

I claim:

1. In a printing-machine, the combination of a type-carrying member having characters arranged in a concentric series, and operating-mechanism adapted to swing said member, about the center of said series, to bring its characters selectively into operative position, and to move said member 120 transversely to said series, while in engagement with the work, to feed the work.

2. In a printing-machine, the combination of a type-wheel having a series of characters on its periphery, and operating-mech- 125

nism adapted to rotate the wheel, to bring its characters selectively into operative position, and to move the wheel axially, while in engagement with the work, to feed the work.

5. 3. In a printing-machine, the combination of a type-wheel having characters arranged in a series extending around its periphery, a platen-roller coöoperating with the type-wheel and journaled on an axis lying in a plane normal to the axis of the type-wheel, and operating-mechanism adapted to rotate the type-wheel, to bring its characters selectively into coöperative relation with the platen-roller, and to move the type-wheel axially, while in engagement with the work, to feed the work.

4. In a printing-machine, the combination of a type-carrying member having characters arranged in a series, a manually-operable member movable both angularly and longitudinally with respect to a fixed axis, and connections, between the type-carrying member and the manually-operable member, whereby one of said movements of the latter is translated to a selective movement of the type-carrying member in the direction of the length of said series, and the other of said movements of the manually-operable member is translated to an impressing movement 30 of the type-carrying member in a direction transverse to the length of said series.

5. In a printing-machine, the combination of a type-wheel provided with a peripheral series of characters and movable both rotatively and axially, a manually-operable member adapted to both slide along, and swing around, a fixed axis, and connections, between the type-wheel and said member, adapted to translate the two movements of the latter, the one into rotative movement, and the other into axial movement of the wheel.

6. In a printing-machine, the combination of a type-wheel provided with a peripheral series of characters and movable both rotatively and axially, a pinion connected with the type-wheel, a rack meshing with said pinion, means for supporting the rack, adapted to permit both longitudinal movement thereof, to rotate the pinion and the type-wheel, and lateral movement, to move the type-wheel axially, and manually-operable means for imparting such movements to the rack.

55. 7. In a printing-machine, the combination of a type-wheel provided with a peripheral series of characters and movable both rotatively and axially, the type-wheel being also provided with an annular groove and with 60 gear-teeth at the bottom of the groove, a rack having a toothed edge which coöperates with said gear-teeth and which is partially cylindrical in cross-section and adapted to engage the walls of said groove, a 65 shaft, parallel with the toothed edge of the

rack, upon which the rack is mounted to both slide and rock, so as to impart both rotative and axial movements to the type-wheel and manually-operable means for so moving the rack.

70. 8. In a printing-machine, the combination of a type-wheel, a pinion by which it may be rotated, a rack coöperating with the pinion, manually-operable means for moving the rack longitudinally, a pointer attached to the rack, and a fixed scale along which said pointer moves, when the rack is moved longitudinally, to indicate the resultant position of the type-wheel.

80. 9. In a printing-machine, the combination of a type-wheel movable both rotatively and axially, and having a cylindrical periphery carrying types arranged to read transversely upon said periphery, a plate fixed to the type-wheel and having peripheral teeth corresponding in position with the characters upon the type-wheel, a fixed detent-member adapted to pass between said teeth and the types upon the type-wheel when the wheel is moved axially in one direction, and manually-operable means for imparting rotative movement to the type-wheel to bring the types selectively into operative position, and for imparting axial movement to the type-wheel to feed the work when engaged by the type-wheel.

10. In a printing-machine, a type-carrying member having a surface upon which types are arranged in a series of lines with intervening spaces, means for moving said member in the direction of the length of said series to bring the type-lines selectively into operative position, and for then moving said member in the direction of the selected type-line to feed the work in engagement therewith, a fixed detent-member adapted to be received in one of the spaces between the type-lines during said feeding movement, whereby a proper operative position of the type is insured, and a detent-member, of harder material than the types, carried by the type-carrying member and provided with a series of recesses alining with the spaces between the type-lines, and a series of projections alining with the type-lines, and adapted to engage a fixed detent-member and arrest the feeding movement of the type-carrying member when said member is not in proper printing position.

11. In a printing-machine, a type-wheel 120 provided with a series of characters upon its periphery and adapted to move both rotatively and axially for the purpose of selective and feeding operations, an ink-roller normally engaging the periphery of the type-wheel, the wheel and the roller being provided with coöperating abutments whereby the ink-roller is normally constrained to move axially with the type-wheel, a shaft upon which the ink-roller is free to both ro- 130

tate and slide, a casing normally inclosing the type-wheel of the ink-roller and provided with an opening in alinement with the ink-roller, a base-plate mounted in a casing 5 but adapted to slide outwardly through said opening, and means for supporting said shaft upon said base-plate and for yieldingly forcing the shaft and the ink-roller toward the type-wheel.

10 12. In a printing-machine, the combination of a type-carrying member provided with a series of characters, means for moving said member to bring the characters selectively into operative position and to move 15 the operative character, when in such position, in a direction to feed the work in engagement therewith, and for moving said member in the opposite direction to return said character to normal position, a platen 20 adapted to press the work against the operative character, and means for moving the platen toward the type-carrying member at the beginning of the feeding movement, and for releasing the platen from operative position at the beginning of the return movement of the type-carrying member.

25 13. In a printing-machine, the combination of a type-carrying member, a platen

adapted to coöperate therewith in impressing and feeding the work, a work-pressing member adapted to engage the work and to hold it against accidental movement, and manually-operable means for causing feeding and return movements of the type-carrying member, and for throwing the platen 30 and the work-pressing member alternatively 35 into operation during the feeding and return movements, respectively.

14. In a printing machine, the combination of means for simultaneously impressing 40 and feeding a check-blank, clamping means for retaining the blank, by engagement with a surface thereof, against movement in the line of feed, and manually-operable mechanism for throwing said means alternatively 45 into operation, the retaining-means being located normally in a position beyond that occupied by the advance end of the blank at the beginning of the printing-operation, so that the blank may be freely introduced 50 into the machine while the retaining-means are in operative position.
